DESIGN FOR A CLOCK HOUSING

Marion Murray, San Jose, Calif.

Application December 17, 1945, Serial No. 124,800

Term of patent 14 years

(Cl. D42—7)

To all whom it may concern:

Be it known that I, Marion Murray, a citizen of the United States, residing at San Jose, in the county of Santa Clara and State of California, have invented a new, original, and ornamental Design for Clock Housing, of which the following is a specification, reference being had to the accompanying drawing, forming part thereof.

Fig. 1 is a front elevational view of a clock housing showing my new design.

Fig. 2 is a side elevation of the clock housing shown in Fig. 1.

Fig. 3 is a top view of the clock housing shown in Fig. 1.

Fig. 4 is a bottom view of the clock housing shown in Fig. 1.

I claim:

The ornamental design for a clock housing, as shown.

MARION MURRAY.
